DESIGN FOR A BICYCLE SADDLE

Benjamin N. Lobdell, Alma, Mich., assignor to
The Lobdell-Emery Manufacturing Company,
Alma, Mich., a corporation of Michigan

Application June 23, 1939, Serial No. 85,655

Term of patent 3½ years

To all whom it may concern:

Be it known that I, Benjamin N. Lobdell, a citizen of the United States and resident of Alma, county of Gratiot, State of Michigan, have invented a new, original, and ornamental Design for a Bicycle Saddle, of which the following is a specification, reference being had to the accompanying drawing, forming a part thereof, and in which:

I claim:

The ornamental design for a bicycle saddle, substantially as shown.

BENJAMIN N. LOBDELL.
